UNITED STATES PATENT OFFICE.

THOMAS F. SCOLLARD, OF WARSAW, INDIANA.

ROTARY VALVE.

1,362,899.

Specification of Letters Patent. Patented Dec. 21, 1920.

Application filed September 10, 1919. Serial No. 323,009.

To all whom it may concern:

Be it known that I, THOMAS F. SCOLLARD, a citizen of the United States, residing at Warsaw, in the county of Kosciusko and State of Indiana, have invented a new and useful Rotary Valve, of which the following is a specification.

This invention relates to valves and it is the principal object of the invention to provide a valve construction of the rotary type having efficient means for cooling the valve, to prevent the heating of the valve, thereby insuring against sticking of the contacting valve members, due to expansion thereof, caused by excessive friction.

A still further object of the invention is to provide removable sleeve members, which may be readily moved and replaced in the event that the same become worn or otherwise rendered inoperative.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

Referring to the drawings:—

Figure 1 illustrates a longitudinal sectional view through a valve constructed in accordance with the present invention.

Fig. 2 is a transverse sectional view taken on line 2—2 of Fig. 1.

Fig. 3 illustrates a perspective view of the valve member proper.

Fig. 4 illustrates a perspective view of one of the sleeve members.

Fig. 5 illustrates a side elevational view of the valve member showing the operating rod, as connected thereto.

Fig. 6 illustrates a perspective view of the upper end of the valve casing.

Fig. 7 illustrates a perspective view of the cover for the valve, and

Fig. 8 illustrates a side elevational view of a spring employed in connection with the cover.

Referring to the drawings in detail, the device is illustrated by Fig. 2 as employed in connection with a pair of cylinders of a gas engine, the numerals 5 and 6 thereof designating the intake pipes of the cylinders, the same being supplied with fuel

through the rotary valve forming the subject matter of the present invention.

The rotary valve includes the circular casing 7, which comprises the outer wall 8, and inner wall 9, the same being spaced apart to provide a cooling surface. The inner wall 9, is provided with a cut-out portion 10 adapted to receive a quantity of gas passing through the valve.

Disposed within the inner wall 9, adjacent the upper end thereof, is the key slot 12, which slot registers with a key slot 13, formed in the sleeve member 14, to receive the key 15, which key connects the sleeve member 14, to receive the inner wall 9 of the casing, to prevent rotary movement, of the sleeve 14, with relation to the casing, when the valve is being operated.

A sleeve member 16, is positioned within the sleeve member 14 and conforms with the shape thereof, to provide a close fit therebetween, to insure against the charge leaking at this point.

This sleeve member 16, as clearly shown by the detail view of Fig. 4 of the drawings, is provided with a plurality of cut-out portions 17, disposed adjacent the upper edge thereof to permit a passage of water, which is employed in connection with the valve, as a cooling medium to pass therethrough.

As shown, the sleeve 14, is provided with lateral discharge openings 14' and 15' having communication with the cylinder inlet pipes 5 and 6, leading to the engine cylinders. The sleeve 16, keyed to the valve proper is also provided with lateral openings 16' and 17', which openings are adapted to register with the openings 14' and 15' of the sleeve 14, during the rotation of the valve, for distributing a charge to the cylinders of the engine.

The valve proper, includes a hollow cone shaped member 18, having a central passageway 19, and an upper passageway 20, the central passageway having communication with the intake pipe 21, leading from a carburetor, or similar charge forming device, while the upper passageway 20, has communication with the pipe 22, which has connection with a suitable water supply not shown.

This passageway 20, has communication with the chamber 23 formed at the base of the valve, through the vertical passageway 24' and as shown, said chamber 23, has communication with a discharge pipe 25,

through which the fluid passes, after the same has accomplished the cooling result, in its passage through the passageways 20 and 24.

5 The valve proper is so constructed that the passageway 24 will move to a position to close the intake ports of the engine cylinders associated with the valve, while the cylinders are being fired, and to this end the 10 passageway at 24 admits the cooling medium, to contact directly with the valve at its hottest point.

A supporting disk 26, forms the base for the valve and provides means for supporting the same in suitable relation with the engine cylinder, used in connection therewith. The supporting disk, is provided with a central opening 27, which opening is in alignment with a depressed portion 28, 20 formed in the lower end of the valve member 18, and receives the upper end of the operating shaft 29, which has its lower end suitably connected with an operating mechanism, not shown, whereby rotary 25 movement of the shaft 29, imparts a rotary movement to the valve 18, for bringing the discharge port 34, thereof into alignment with the intake pipes 5 and 6, leading to the engine cylinders.

30 Supported on the upper end of the valve 18, is a disk 33, which disk is provided with a central opening 34, to provide communication between the central passageway 19, and the intake pipe 21, whereby fuel from the 35 intake pipe 21, is admitted to the central passageway 19 of the valve.

An opening 35, is formed through the disk 33, and provides communication between the chamber 36, formed between the 40 upper wall, or cover of the valve casing 37, the cover being supported in spaced relation with the disk 33, whereupon moisture or vapor present in the passageway 20, passes upwardly into the chamber 36, where the 45 same mingles with the incoming charge with the result that the charge is moistened, before the charge enters the engine cylinders. It will therefore be seen that due to the charge being moistened, carbon deposits 50 within the cylinder are reduced.

A plurality of pins 38, extend upwardly from the disk 33, the upper ends thereof lying within openings 39, formed in the lower surface of the disk 37, whereby the 55 disk 33 is prevented from rotary movement, when the valve member 18 is operated.

It might be further stated that a coil spring 48, surrounds each of these pins 39, for exerting pressure on the disk 33, therefore 60 by holding the disk into close engagement with the upper end of the valve member 18.

The valve 18, is provided with a key hole slot 41, registering with the key hole slot 42, formed in the sleeve 16, whereby movement

of the valve member 18, is transmitted to 65 the sleeve member 16.

If it becomes necessary to replace one of the sleeve members, due to the same becoming worn or otherwise rendered inoperative, it is only necessary to remove the cover 37, 70 which is secured to the member of the valve, by means of the bolts 43, whereupon the disk 33, may be removed, thereby giving access to the key members which secure the sleeve members to their respective supporting elements. 75

It will thus be seen in operation, the valve member 18, receives a charge through the intake pipe 21, and distributes the same to the various cylinders of the engine, due 80 to the fact that the valve 18, is rotated, to bring the exhaust port thereof, into registry with the intake pipes 31 and 32 leading to the engine cylinders.

Water, or other cooling fluid, enters the 85 chamber 30, through the pipe 22, whereupon the same passes through the valve, and out through the discharge pipe 25, the flow of water being controlled by suitable pump mechanisms, not shown. 90

Having thus described the invention, what is claimed is:—

1. In a rotary valve, a casing, a sleeve positioned within the casing, a valve member positioned within the casing, a sleeve 95 keyed to said valve member and contacting with the first mentioned sleeve, said valve member and sleeves having ports adapted to register, passageways formed within the valve member adjacent to one of said sleeves, 100 a stationary cover for said valve member, means extending into one of the passageways and through the cover for supplying a cooling medium to the valve, and means for supplying fuel to the valve member. 105

2. In a rotary valve, a casing, a sleeve positioned within the casing and keyed thereto, a valve member within the casing and having a sleeve keyed thereto, said sleeves contacting to provide a leak-proof 110 connection, said valve member having a lateral opening, said sleeves having openings registering with the opening in the valve member to permit the passage of fuel therethrough, a circular cover for the valve member, means for normally forcing the cover into engagement with the upper edge of the valve member, and a pipe extending through the cover for supplying a cooling fluid to the valve member and sleeves. 115 120

In testimony that I claim the foregoing as my own, I have hereto affixed my signature in the presence of two witnesses.

THOMAS F. SCOLLARD.
